UNITED STATES PATENT OFFICE.

CHARLES A. SIEWECK, OF NEW YORK, N. Y., ASSIGNOR TO F. A. D. ANDREA, INC., OF NEW YORK, N. Y., A CORPORATION OF NEW YORK.

DESIGN FOR A RADIO-RECEIVING-APPARATUS CABINET.

Application filed August 19, 1924. Serial No. 10,494. Term of patent 3½ years.

To all whom it may concern:

Be it known that I, CHARLES A. SIEWECK, a citizen of the United States, and resident of the city of New York, in the county of New York and State of New York, have invented a new, original, and ornamental Design for Radio-Receiving-Apparatus Cabinets, of which the following is a specification, reference being had to the accompanying drawing, forming part thereof.

The figure is a perspective view of the radio receiving apparatus cabinet, showing my new design.

I claim:—

The ornamental design for a radio receiving apparatus cabinet, as shown.

Signed at the city of New York, in the county of New York, and State of New York, this 12th day of August, A. D. 1924.

CHARLES A. SIEWECK.
